United States Patent

Des. 236,400
Patented Aug. 26, 1975

236,400

DINING TABLE

Simon V. Waitzman, 195 Hicks St.,
Brooklyn, N.Y. 11201

Filed May 9, 1973, Ser. No. 358,718

Term of patent 14 years

Int. Cl. D6—03

U.S. Cl. D6—177

FIG. 1 is a view in perspective of a dining table, showing my new design;

FIG. 2 is a side elevational view thereof; and
FIG. 3 is a top plan view thereof.

I claim:

The ornamental design for a dining table, substantially as shown.
